IGNITION AND FLAME DETECTION MEANS FOR GAS BURNERS

This invention relates to automatic control systems for fluid fuel burners which include electrical ignition means for igniting the burner and a safety time switch operative to permit the supply of fuel to the burner for a predetermined short trial period during which the igniter is operated, and thereafter provided combustion of the fuel occurs within the trial period, and to cut off the supply of fuel if combustion fails to occur within the trial period or, if having occurred, subsequently fails.

The U.S. Pat. No. 3,393,039, issued July 16, 1968 to R. W. Eldridge, Jr., et al., discloses a burner control system of this kind; in which, conduction of an SCR effects the opening of the fuel valve, the heating of a thermal time switch, and the discharge of a capacitor through the primary winding of an igniter transformer to effect sparking across electrodes in a secondary circuit. In the Eldridge et al. system a neon bulb is employed to trigger the SCR, and a relatively slow-responding, temperature responsive switch is employed to cut off conduction of the SCR upon the appearance of burner flame.

While a neon bulb functions satisfactorily as an SCR triggering means, it has been found that variations in the firing voltage of commercially available neon bulbs, due to manufacturing tolerances, results in variations in the firing angle of the SCR and, consequently, variations in the length of time current is passing through the time switch heater each cycle. Also, the use of any voltage responsive triggering means for the SCR would result in considerable variation in the firing angle of the SCR as the line voltage varied, even though the firing voltage of such triggering means is closely controlled. Variations in the length of time current is passing through the thermal time switch appreciably affect the length of the trial period, which in the interest of safety is made as short as practicable. It is of particular importance when employing instantly responsive flame detection means to cut off SCR conduction upon the appearance of flame that heating of the time switch be maintained as uniform as possible so that the safer, shorter trial period that an instantaneous flame detector makes possible can be used.

Moreover, when employing a neon bulb or other voltage responsive SCR triggering means, it is necessary to select one with a nominal firing voltage safely below the lowest peak supply voltage likely to occur so as to insure operation of the system under conditions of variable power supply voltage. This, then, results in the firing of the SCR at a line voltage which is considerably below the nominal peak which, in turn, results in less charge on the igniter capacitor and less energy of the pulse through the igniter primary and, consequently, a reduction in ignition spark intensity below that which would occur if the SCR were always fired near peak line voltage.

An object of this invention is to provide a generally new and improved electrical control system for fluid fuel burners, in which: the firing of an SCR supplies electrical pulses for the operation of a spark igniter and conduction thereof effects the opening of an electrically operated fuel valve and the heating of an electrically heated thermal time switch; and in which the firing of the SCR is caused to occur at substantially midway of it conducting half cycle irrespective of supply voltage.

A further object is to provide an electrical control system for fluid fuel burners, in which: an SCR, when conducting, heats a thermal time switch to effect the cutoff of fuel to a burner at the termination of a predetermined trial period in which to effect combustion of the fuel; and in which novel means responsive to electrical conduction through burner flame operates to cut off conduction of the SCR, thereby to render the time switch inoperative upon the appearance of burner flame.

Further objects and advantages will appear when reading the following description in connection with the accompanying drawing.

The single FIGURE of the drawing is a schematic illustration of a burner control system constructed in accordance with the present invention.

Referring to the drawing, a gas burner is indicated at 10, having a gas supply line 12 leading thereto. Interposed in gasoline 12 is a biased closed, electromagnetically opened valve 14 including a solenoid winding 16 which when sufficiently energized effects opening of valve 14. Fuel issuing from the ports of burner 10 is ignited by a spark igniter which includes a voltage step-up transformer having a primary winding 18, a secondary winding 20, and a pair of spaced electrodes 22 connected across secondary winding 20.

- 10 The solenoid winding 16 is connected across terminals 24 and 26 of an AC electrical power supply through a circuit which may be traced as follows: from terminal 24 through a lead 28, a lead 32, a diode 34, a lead 36, an adjustable resistor 38, a lead 40, solenoid winding 16, a lead 42, the electrical resistance safety switch heater 44, a lead 46, a current limiting resistor 48, the leads 50 and 52, the safety switch 54, the leads 56, leads 58 and 59, thermostat 30, and lead 60 to power source terminal 26.
- 15 The just-described circuit is a valve "hold open" circuit through which current flow is unidirectional due to diode 34, and through which current flow is limited by the resistor 48 to a value which energizes solenoid winding 16 sufficiently to hold open valve 14 once it has been moved open, but is less than a value required to energize winding 16 sufficiently to effect opening of valve 14 from its biased closed position. Also, the unidirectional current flow through the just-described circuit partially heats the safety switch resistance heater 44 and the normally closed adjacent bimetal safety switch blade 54, but this current flow is insufficient to effect the warping open of switch blade 54 irrespective of time.

The primary winding 18 of the igniter transformer is connected in parallel with current limiting resistor 48 through an SCR 62 by the leads 63, 64, and 66. When SCR 62 is conducting, sufficient additional unidirectional current flows through solenoid winding 16 to effect the opening of valve 14 from its biased closed position. Also, the additional unidirectional current flow through safety switch resistance heater 44, which occurs when SCR 62 is conducting, effects the warping open of bimetal safety switch blade 54 in a predetermined relatively short period of time. The safety switch blade 54 when sufficiently heated by resistance heater 44 to warp open is locked in an open position by the pivoted latch 55, thereby requiring manual resetting. The safety switch 54 is arranged to deenergize the entire system when opened.

In the absence of burner flame the SCR 62 is caused to fire midway of each conducting half cycle and is continuously biased to continue conducting throughout the remainder of each conducting half cycle by means which will be hereinafter described. Upon the occurrence of burner flame, conduction of SCR 62 is cut off substantially instantly by means which will also be hereinafter described.

Connected in parallel with SCR 62 and with the igniter transformer winding 18 by leads 68 and 70 is a capacitor 72, which charges during that portion of each conducting half cycle prior to the firing of SCR 62 and discharges through transformer primary winding 18 upon the firing of SCR 62, thereby providing a strong energy pulse which passes through primary winding 18 and effects an ignition spark across electrodes 22 in the circuit of transformer secondary winding 20. The capacitor 72 charges through the series connected safety switch resistance heater 44, solenoid valve winding 16, adjustable resistor 38, and diode 34, and discharges through a relatively low-impedance loop comprising the transformer primary winding 18 and SCR 62.

The firing of SCR 62 at substantially peak supply voltage, irrespective of variations in supply voltage, is accomplished by employing a transistor 74 which, when fired, fires the SCR, and in providing an RC timing circuit comprising a capacitor 76, an adjustable resistor 78, and a fixed resistor 80 to produce a firing signal for transistor 74 at substantially midway of the half cycle during which SCR 62 may be made conductive. The capacitor 76 and resistors 78 and 80 are series connected across the power supply by leads 82, 84, 86, 88,

and 90. The transistor 74 is an NPN type having its emitter connected to the control electrode of SCR 62 by a lead 92, its collector connected to a point between voltage dividing resistors 96 and 98 by a lead 94, and its base connected to a point between capacitor 76 and resistors 78 and 80 forming the RC timing circuit. The base of transistor 74 is connected to the RC timing circuit through a pair of resistors 100 and 102 by leads 104, 106, and 108. The voltage dividing resistors 96 and 98 are connected across the power source in series with diode 34 and leads 110, 112, 114, and 116.

The collector of transistor 74 is, therefore, forward biased during the conducting half cycle of SCR 62, and its base becomes forward biased when the charge on capacitor 76 crosses the zero voltage line from negative to positive. Inasmuch as the voltage across capacitor 76 lags the voltage across resistors 78 and 80 and the line voltage by approximately 90°, the charge on capacitor 76 will become positive at substantially midway of the conducting half cycle of SCR 62 and at substantially peak line voltage. The values of resistors 80 and 78 and capacitor 76 are such that a firing signal is applied to the base of transistor 74 within a few degrees after the charge on capacitor 76 becomes positive. Because the positive signal required to fire transistor 74 is quite small, the firing angle of transistor 74 and consequently that of SCR 62, will remain substantially constant under the usual supply voltage variations encountered.

The cutoff of SCR conduction upon the appearance of burner flame is accomplished by shunting the signal voltage applied to the base of transistor 74 through a P-channel, junction-type, field effect transistor 116 connected in parallel with capacitor 76 by leads 118 and 120. The normally conductive FET 116 is biased off, in the absence of burner flame, by connection of its gate to power source terminal 24 through resistors 122 and 124, and leads 126, 128, 130 and 132, and through voltage dividing means comprising resistors 136, 138, and 140, which are connected across the power source by leads 142, 144, 146, 92, 148, and 150. The FET gate is also connected to the terminal 26 side of the power supply through resistor 122, a small capacitor 152, and leads 154 and 156. The small capacitor 152 charges during the conducting half cycle of diode 34 through resistor 124, of high resistance, and maintains a positive bias on the FET gate through the nonconductive half cycle of diode 34 in the absence of flame.

The gate of FET 116 is further connected to the right-hand spark electrode 22 in the ignition transformer secondary circuit through a resistor 158 and leads 160 and 162. The burner 10 and the terminal 24 side of the power supply are suitably grounded at 164 and 166, respectively, whereby a small electrical current will be caused to flow during the nonconductive half cycle of SCR 62 and diode 34 from a point of junction 169 through lead 160, resistor 158, lead 162 to spark electrode 22, thence through burner flame, when it exists, to burner 10 and to ground, thence through ground to supply terminal 24. Due to flame rectification a much greater ion flow occurs from electrode 22 to burner 10 than will flow oppositely. The flame-conducted current flowing through the described path sufficiently reduces the positive charge on the FET gate to permit it to conduct. Conduction through FET 116 shunts the firing signal applied to transistor 74, thereby cutting off conduction thereof and, consequently, cutting off conduction of SCR 62. Inasmuch as conduction through a burner flame characteristically varies considerably as the flame flutters, the capacitor 152, besides storing a charge to maintain a positive bias on FET 116 during the nonconducting half cycle, also functions to filter current flow through the burner flame.

A neon bulb 170 connected between the spark electrode 22 and the terminal 26 side of the power supply by leads 172 and 174 functions to protect the FET 116 and the circuit wiring from high voltage which may occur if the high-tension electrode 22 becomes grounded. A capacitor 176 connected across the power source by leads 178 and 180 protects the entire system against transient voltages incidental to switching.

as at the thermostat 30. A diode 182 connected across the solenoid valve winding 16 in opposite polarity by leads 184 and 186 permits the continued flow of current through winding 16 occasioned by the coil inductance and thereby reduces the tendency of the solenoid to chatter at the lower supply voltages.

OPERATION

The closing of thermostat 30 in response to a drop in the temperature of the space being heated by burner 10 effects the supply of fuel to burner 10 and the operation of the spark igniter. There being no burner flame FET 116 is biased off, thereby permitting the application of a firing signal to the base 15 of transistor 74 as the voltage on capacitor 76 crosses the zero line from negative to positive midway of the conducting half cycle of SCR 62. The firing of transistor 74, in turn, effects the firing of SCR 62. The sum of the unidirectional currents now 20 passing through resistor 48 and parallel connected SCR 62 is sufficient to pull open the valve 14 and effect the warping open of safety switch blade 54 in short, predetermined period of time.

Since zero voltage across capacitor 76 and maximum supply voltage substantially coincide midway of the conducting half 25 cycle of diode 34, and since the transistor 74 is fired within a few degrees after the zero voltage crossing of capacitor 76, the firing of SCR 62 will occur at substantially maximum line voltage. Also, inasmuch as the phase relationship of the supply 30 voltage and the voltage across capacitor 76 remains substantially constant under conditions of supply voltage variation and inasmuch as the signal voltage required to fire transistor 74 is quite small, the firing angle of SCR 62 will remain substantially constant and will occur at substantially maximum line voltage irrespective of line voltage variations, within 35 prescribed limits, of course.

The minimizing of variations in the firing angle of SCR 62 permits closer calibration of the safety switch heater 44 to provide a shorter trial period and reduces variations in current 40 flow through solenoid valve winding 16, which encroach upon the required differential between pull-open and hold-open current values. Moreover, the firing of SCR 62 uniformly midway of the conducting half cycle, and at peak voltage, permits fully charging capacitor 72 and the application of the maximum 45 energy pulse to the igniter transformer.

Upon the firing of SCR 62 the voltage on the anode side thereof momentarily falls through zero to a negative value, but the impedance between the SCR 62 and terminal 24 is relatively low and permits a rapid recovery. Also, the firing signal 50 applied through transistor 74 persists through this transient condition and throughout the remainder of the conducting half cycle, so that the current flow through SCR 62 continues steady.

When burner flame appears a small current will be caused 55 to flow from junction 169 through resistor 158 to the right-hand electrode 22, and, thence, through the burner flame to ground during the nonconductive half cycle of diode 34. The circuit controlling the gate of FET 116 being a high-impedance network, this small current flow discharges capacitor 152 to such negative value during the nonconducting half cycles of diode 34 that it does not charge positively sufficiently 60 during the conducting half cycles of diode 34 through high value resistor 124 to hold FET 116 in a biased off condition.

FET 116, therefore, becomes conductive and shunts the firing signal otherwise applied to transistor 74. Consequently, conduction through SCR 62 is cut off substantially instantly upon the appearance of burner flame. The fuel valve 14 will now be held open by the current flow through resistor 48. The amount of current flowing through resistance heater 44, under these conditions, will not effect the opening of safety switch blade 54, so the burner will now continue to operate until thermostat 30 opens.

In event the fuel at burner 10 fails to ignite within the 75 predetermined trial period following the closing of thermostat

30, the bimetal switch blade 54 will be warped open and latched open, disconnecting the entire system from the power source and permitting the biased closed fuel valve to close.

It will be understood that the values of resistors 138 and 136, connecting the gate of SCR 62 to the anode side thereof, are sufficiently high in relation to the value of resistor 140, connecting the gate to the anode side, to preclude the application of a firing signal to the SCR 62 when transistor 74 is not conducting. Also, the resistor 124 and capacitor 152 have values in the order of 20 megohms and 0.03 mfd., respectively, whereby the very small current conducted through the burner flame is sufficient to reduce the charge on capacitor 152 below that required to bias off the FET 116.

It was found that with certain types of burners a greater and more consistent flow of current through the burner flame resulted when the burner itself formed one of the spaced electrodes spanning the flame. Consequently, the burner 10 and the supply line (ahead of diode 34) were conveniently grounded at 164 and 166 to provide a path parallel to blocking diode 34 for flame conducted current to flow during the nonconductive half cycle. Also, with this arrangement, the capacitor 152 is required to hold the off bias on the FET gate during the nonconductive half cycle when no flame exists.

It will be understood, however, that with other types of burners, adequate flame conduction may be achieved by employing two electrodes, other than spark electrodes, spaced in the burner flame and in connecting them between junction point 169 and supply lead 50 in series with resistors 124 and 136 across the power supply, whereby a small flow of current through the burner flame during the conductive half cycle will preclude the application of a biasing off voltage to the FET gate through the high-value resistor 124. In this alternate arrangement the capacitor 152 is eliminated and the grounding of the burner 10 and supply line at points 164 and 166 is omitted. Also, the thermostat 30 is preferably moved to the terminal 24 side of the line in this alternate arrangement.

I claim:

1. In a flame detection circuit for fluid fuel burner an AC power source, a burner, means to supply fuel to said burner, an SCR operative when conducting to effect the cutoff of fuel to the burner in a predetermined short period of time in the absence of burner flame, a transistor operative when conducting to fire said SCR and maintain conduction thereof, means including high impedance means connecting the base of said transistor to one side of said power source and operative to apply a forward biasing voltage thereto and effect the conduction of said transistor during a portion of the conductive half cycle of said SCR, a normally conductive FET connected between said transistor base and the opposite side of said power source and operative when conducting to shunt the forward biasing voltage applied to said transistor base and prevent the firing of said transistor, means including high-impedance means connecting the gate of said FET with said one side of said power source to effect a cutoff bias of said FET during the conductive half cycle of said SCR, a pair of spaced electrodes forming an airgap and arranged to be bridged by burner flame when it exists, and circuit connections including said airgap connecting said FET gate to said other side of said power source and operative to shunt the cutoff bias applied to said FET gate and permit conduction thereof when flame exists.

2. A flame detection circuit as set forth in claim 1 in which a capacitor is connected between the gate of said FET and said other side of said power source; and a diode having the same polarity as said SCR is series connected with said high-impedance means.

pedance means between said FET gate and said one side of said power source, whereby said capacitor is charged through said high-impedance means during the conductive half cycle of said SCR and holds the charge during the nonconductive half cycle of said SCR in the absence of flame, and in which said spaced electrodes forming an airgap arranged to be bridged by burner flame are connected between said FET gate and said one side of said power source and effect the sufficient discharge of said capacitor during each nonconductive half cycle of said SCR when flame exists, thereby to preclude the application of a cutoff bias to said FET gate through said high-impedance means during conductive half cycles.

3. In an electrically operated burner control system, an AC power source, a burner, a bimetal safety switch having an electrical resistance heater, a normally closed solenoid valve having a winding, a current-limiting resistor, a solid-state switch having a control electrode, and ignition means, circuit connections connecting said safety switch, said safety switch heater, said solid-state switch and said solenoid winding in series across said power source, circuit connections connecting said current-limiting resistor in parallel with said solid-state switch, means operative in the absence of burner flame to apply a firing signal to said control electrode of said solid-state switch each conductive half cycle thereof at substantially peak power source voltage, said means comprising a resistor and a capacitor series connected across said power source and circuit connections connecting said control electrode to a point between said resistor and capacitor, and switching means operative in response to the appearance of flame at said burner to render said last-mentioned mentioned means inoperative to apply a firing signal to said control electrode.

4. The burner control system claimed in claim 3 in which said ignition means comprises an igniter transformer primary winding connected in series with and arranged adjacent to said solid-state switch, a capacitor connected in parallel with said solid-state switch and said primary winding, a transformer secondary winding and a pair of spaced spark electrodes connected in series therewith.

5. The burner control system claimed in claim 3 in which said means operative to apply a firing signal to said control electrode of said solid-state switch further includes amplifying means having an input lead connected to said point between said resistor and capacitor and operative in response to an initial small signal voltage appearing across said capacitor to apply a strong firing signal to said control electrode and maintain conduction thereof to substantially the end of the half cycle, and in which said means operative in response to the appearance of burner flame to preclude the application of a firing signal to said control electrode comprises flame responsive switching means operative to preclude the application of any input signal to said amplifying means when burner flame exists.

6. The burner control system claimed in claim 5 in which said flame responsive switching means operative when flame is present to preclude the application of any input signal to said amplifying means comprises a normally conductive solid-state switch having a control electrode, circuit connections including high-resistance means connecting said electrode to one side of said power source and operative to effect a cutoff bias thereto, a pair of spaced electrodes forming an airgap arranged to be bridged by burner flame, and circuit connections including said airgap connecting said electrode to the other side of said power source whereby conduction through burner flame bridging said airgap precludes the application of a cutoff bias to said control electrode when burner flame exists.
